[57] CLAIM

The ornamental design for a fork, as shown and described.

DESCRIPTION

FIG. 1 is a front elevational view of a fork showing our new design;

FIG. 2 is a right side elevational view thereof;

FIG. 3 is a top plan view thereof;

FIG. 4 is a bottom plan view thereof;

FIG. 5 is a front elevational view of an alternate embodiment of a fork, showing our new design;

FIG. 6 is a right side elevational view of the alternate embodiment;

FIG. 7 is a top plan view of the alternate embodiment; and,

FIG. 8 is a bottom plan view of the alternate embodiment.

The rear and left side elevational views are identical to the respective front and right side elevational views of FIGS. 1, 2, 5 and 6, reversed.

FIG. 1

FIG. 2

FIG. 3

FIG. 4

FIG. 5

FIG. 6

FIG. 7

FIG. 8
